UNITED STATES PATENT OFFICE.

HERMANN GROSSMANN AND ALEXANDER GROSSMANN, OF DRESDEN, GERMANY.

ATTACHMENT FOR SEWING MACHINES.

Application filed November 12, 1923. Serial No. 674,379.

To all whom it may concern:

Be it known that we, HERMANN GROSSMANN and ALEXANDER GROSSMANN, citizens of Germany, residing at Dresden, Germany, have invented certain new and useful Improvements in Attachments for Sewing Machines, of which the following is a specification.

Our invention refers to an attachment for sewing machines, and more especially for flower stitch sewing machines for use in the manufacture of straw hats and the like. Its particular object is to improve that part of the mechanism which comprises the guide which in known machines of this kind is sideways adjustable and carries the member for holding the work piece down on the table, as well as a member serving to guide the strip consisting of plaited work or the like which shall be sewed onto the straw hat, this member serving also to separate the strip from the work piece.

In the attachment for sewing machines according to the present invention, this guiding and separating member is arranged to be displaced sideways in order to insure a uniform width of the stitches, both at the work piece and the strip to be connected therewith. This novel strip guide further allows keeping its position also in the case where, instead of a strip of uniform width, so-called inserts shall be sewed on, if the hat shall be broader on one side than on the other. According to the present invention, the depressing member disposed between the strip guide and the left hand end face of the guide is arranged to be removed in order to allow exchanging it, and can be made to swing upwards, the pressure exerted by it upon the strip being variable.

This and further improvements are more fully described hereinafter and illustrated in the accompanying drawings forming part of this specification and illustrating an attachment of the kind aforesaid embodying my invention by way of example. In the drawings

Figure 1 is an elevation partly in vertical longitudinal section, while

Figure 2 is an end elevation,

Figure 3 is a rear view of the left hand portion of the attachment.

Figures 4 to 6 show details.

Referring to the drawings, 1 is the upper part of the guide or carrier which is displaceably mounted sideways of the sewing

machine, as usual. 44 is the member which serves for holding the work piece applied to the table or needle plate, this member being arranged for lateral displacement and adjustment. In the concave rear surface 2 of the guide a longitudinal boring 3 is provided surrounding a rack 4 which can be displaced by means of the toothed cylindrical portion 5 of the spindle 6 which meshes with the rack 4 and can be operated by means of the head 7. The free end of the rack 4 carries the scythe-shaped strip guide 8. A screw 10 projecting into the annular groove 9 of the spindle 6 prevents this latter from being withdrawn from its seat. The portion of the screw 10 which projects into the groove 9 does not fill the entire width of the groove, thus allowing the spindle 6 to be shifted longitudinally to some extent. The coil spring 11 inserted between the head 7 and guide 1 tends to press the head outwards, whereby the lower edge of groove 9 is pressed against the screw 10, thus preventing the rack 4 from being displaced sideways under the action of the shocks acting on the machine during the sewing. The strip guide 8 is thus arranged to be correctly adjusted with regard to the needle, in order to insure a uniform width of stitch.

The arm 13 disposed between the strip guide 8 and the left hand end plate 12 of the guide 1 and which serves to keep the strip applied against the needle plate is bent off at right angles from a toothed rod 14 of quadrangular section. This rod is disposed in the quadrangular opening 15 of a sleeve 16 located in the cylindrical boring 17 of the projecting portion 18 of the guide. The spring 19 fixed to the inner wall of the sleeve projects with slight pressure between the teeth of rod 14 and prevents it from shaking and from any undesirable movements relatively to sleeve 16 without, however, preventing it from being removed for the purpose of replacing it. On rod 14 being withdrawn, the teeth acting on the free end of spring 19 causes it to recede into an indenture 43 provided in the wall of sleeve 16.

A threaded pin 21 projecting from below into a circumferential groove 20 of sleeve 16 prevents this latter from being displaced laterally, while allowing it to turn about its longitudinal axis. As this turning movement extends only over part of a circle, the groove 20 does not extend entirely around the sleeve.

To the right of the bearing 18 a flanged disc 22 is located on sleeve 16, this disc surrounding the bevelled end 23 of bearing 18 and carrying on its free end a projection 24. 5 The cylindrical wall of this disc is perforated and the perforation is provided with a screw thread into which the threaded base portion 25 of the handle 26 is screwed. In 10 the hollow 27 of this handle a coil spring 28 is inserted which serves for pressing a pin 29 into a narrow notch 30 of the part 23.

A sleeve 31 is located on the bush 16 one side of the disc 22, and in the left hand portion 32 of sleeve 31 there is disposed a clock spring 33 having one end inserted in sleeve 16, while the other end projects into a lateral indenture 34 of bush 31. The bush 31 is further provided with several indentures 36 corresponding to the projection 24 on the 20 part 22 (Fig. 5). In the right hand portion 37 of sleeve 31 there is disposed a coil spring 38 surrounding sleeve 16, one end of the spring resting against a ring 40 fixed on the right hand end of sleeve 16 by means of a 25 screw 39, this spring serving to press sleeve 31 against the piece 22, the pressure exerted by the spring being controlled by the position of ring 40. The spring pressure can thus be regulated in order to safeguard 30 operation between projection 24 and indentures 36 under all circumstances and although the spring tension might decrease.

If sleeve 31 is pulled to the right against the action of spring 38, it will pass across ring 40 and will release the projection 24, being now free to be turned about sleeve 16 by itself, in order to place another indenture 36 opposite projection 24, whereby the tension of spring 33 and with it the pressure 40 exerted by the member 13 on the strip to be sewed on is lessened or increased.

In order to cause the member 13 to swing upwards, the handle 26 is pressed down, the pin 29 leaving notch 30. By further turning the disc 22 which carries sleeve 31 along with it, spring 33 is placed under tension until it forces sleeve 16 to partake in the turning of sleeve 31 whereby also rod 14 is turned about its longitudinal axis, carrying 50 arm 13 into the position shown in dotted lines in Fig. 2. While the parts are in this position, the pressure exerted by pin 29 upon the circumference of bevelled end 23 of the bearing 18 prevents any undesirable displacement of the parts. When handle 26 is moved back, sleeve 16 will be turned back also together with disc 22 and bush 31, whereby arm 13 is caused to apply itself against the strip to be sewed on. By handle 60 26 being swung back further until its pin 29 again enters notch 30, the predetermined pressure exerted on it by spring 33 is maintained.

The upper portion 1 of the guide which 65 supports the members 8 and 13 is pivoted to

the base 42 displaceably mounted on the machine by means of a vertical bolt 41 and can thus be swung around in a horizontal plane in the direction towards the operator. In view of the fact that the strip to be sewed 70 on extends across the guide rod 4, the upper portion 1 cannot be swung upwards, as in former machines.

We wish it to be understood that we do not desire to be limited to the exact details 75 of construction shown and described, for obvious modifications will occur to a person skilled in the art.

We claim:—

1. Attachment for sewing machines comprising a guide, a rack adapted to slide in said guide, a plate on the outer end of said rack, means for displacing said rack, a sleeve rotatably carried in said guide and extending in parallel with said rack, means for rotating said sleeve, a bar held against rotation in said sleeve and adapted to slide therein; and an arm at the outer end of said bar.

2. Attachment for sewing machines comprising a guide, a rack adapted to slide in said guide, a plate on the outer end of said rack, a pinion rotatably carried in said guide and adapted to mesh with said rack, means for rotating said pinion, a sleeve rotatably carried in said guide and extending in parallel with said rack, means for rotating said sleeve, a bar held against rotation in said sleeve and adapted to slide therein, and an arm at the outer end of said bar.

3. Attachment for sewing machines comprising a guide, a rack adapted to slide in said guide, a plate on the outer end of said rack, a pinion adapted to mesh with said rack, a spindle secured to said pinion, said spindle being rotatably carried and adapted to slide in said guide, a shoulder on said spindle, a pin in said guide adapted to engage said shoulder, a spring adapted to exert axial pressure on said spindle so as to hold said shoulder against said pin, a sleeve rotatably carried in said guide and extending in parallel with said rack, means for rotating said sleeve, a bar held against rotation in said sleeve and adapted to slide therein, and an arm at the outer end of said bar.

4. Attachment for sewing machines comprising a guide, a rack adapted to slide in said guide, a plate on the outer end of said rack, means for displacing said rack, a sleeve rotatably carried in said guide and extending in parallel with said rack, means for rotating said sleeve, a bar of polygonal cross section adapted to slide in a corresponding hole in said sleeve, an arm at the outer end of said bar, a bush having notches at its inner end and rotatably carried on said sleeve, a spiral spring resiliently connecting said sleeve with said bush, a flanged disc 130

rotatably carried on said sleeve, means for rotating said disc and for temporarily securing said disc against rotation relatively to said guide, and a tooth on said disc 5 adapted to engage one of the notches at the end of said bush.

5. Attachment for sewing machines comprising a guide, a rack adapted to slide in said guide, a plate on the outer end of said 10 rack, means for displacing said rack, a sleeve rotatably carried in said guide and extending parallel with said rack, means for rotating said sleeve, a bar of polygonal cross section adapted to slide in a corresponding 15 hole in said sleeve, an arm at the outer end of said bar, a bush having notches at its inner end and rotatably carried on said sleeve, a spiral spring resiliently connecting said sleeve with said bush, a flanged disc 20 rotatably carried on said sleeve, a handle secured to said disc, a spring-actuated locking pin in said handle adapted to engage a recess in said guide, and a tooth on said disc adapted to engage one or the other 25 notch at the end of said bush.

6. Attachment for sewing machine comprising a guide, a rack adapted to slide in said guide, a plate on the outer end of said rack, means for displacing said rack, a sleeve rotatably carried in said guide and extending in parallel with said rack, means for rotating said sleeve, a bar of polygonal cross section adapted to slide in a corresponding hole in said sleeve, an arm at the outer end of said bar, a bush having notches at 30 its inner end and rotatably carried on said sleeve, a spiral spring resiliently connecting said sleeve with said bush, a flanged disc rotatably carried on said sleeve, means for rotating said disc and for temporarily securing said disc against rotation relatively to said guide, a tooth on said disc adapted to engage one or the other notch at the end of said bush, a coiled spring tending to force said bush against said tooth, and 35 means for varying the tension of said spring. 40

In testimony whereof we affix our signatures.

HERMANN GROSSMANN.
ALEXANDER GROSSMANN.
